PHOTOGRAPHIC MATERIAL FOR PRODUC-
ING DYESTUFF IMAGES

Béla Gaspar, Berlin, Germany

No Drawing. Application March 23, 1933, Serial
No. 662,395. In Germany March 24, 1932

7 Claims. (Cl. 95—7)

This invention relates to photographic material for producing dyestuff images, and more particularly positive images.

It is known in the production of dyestuff images to employ diffusely colored recording or copying material.

In producing images, and more particularly reversed images, there are usually employed silver images, which are subsequently toned. The shades which are obtained by toning or developing are limited in number and the production requires an appreciable length of time. It is also not always possible to obtain the desired shade of color as a necessary result of the method employed.

Reversed images produced on paper, such as bond paper, and in special rapid processes also have the disadvantage that they do not always result in pure whites.

20 The object of this invention resides in the production of dyestuff images, which contain blackish or black dyestuffs.

25 In coloring photographic material with dark or blackish colors, as necessary more particularly for the production of single-color or black-and-white color images, an extremely long time is required for the exposure.

Now it has been found that short periods of 30 exposure may be obtained approximately equal to those associated with normal photographic materials, if the material is sensitized in respect of infra-red rays. In addition to this, sensitization may also be performed in respect of any 35 other gaps which may be present in the absorption range of the dyestuff.

Example 1

The dyestuff Naphthylamine Black 4B (Schultz-Farbstofftabellen 1920 edition, page 405) is added to a silver halide emulsion. As 40 sensitizer there is added the dyestuff Cryptocyanine. The emulsion thus prepared is poured on to a desired backing or support (glass, film or paper).

Example 2

Diamine Black BO (Schultz-Farbstofftabellen 50 1920 edition, page 405) is converted by means of an organic base into an insoluble, non-diffusing salt, for example by conversion with cinchonine chloride, as described in my Patent No. 2,046,067 dated June 30, 1936. This substance is then 55 added to a silver bromide layer.

Example 3

An insoluble dyestuff, such as Sudan Black B, is dissolved in alcohol or acetone, and added to the emulsion. Alternately the same may also be admixed with the emulsion in powder form.

The exposed layers may be treated subsequently according to many different processes. This treatment may consist, for example, in immersing in a bath containing means which destroy the dyestuff by oxidation or reduction at the points of the silver deposit or also at the points which are free of deposit, as described in my Patent No. 2,020,775 dated November 12, 1935 and Patent No. 2,004,625 dated June 11, 1935. The subsequent treatment of the layers may also be performed with the assistance of coupled reactions, such as have already been described by Luther and von Holleben, or also by the use of dyestuff-destroying agents in conjunction with images, which have been preliminarily treated by mordanting or tanning. Beyond this it is also possible to produce in these layers wash-out reliefs by tanning and hardening and subsequent treatment in warm water. The images may be employed for the production of direct positives, for producing duplicate negatives, for the production of master images for photomechanical purposes, for reproducing deed paper, etc.

It will be understood that no limitation is made to the specific examples set forth in the above and that numerous modifications are quite possible within the meaning of the above description and the annexed claims without departing from the spirit of the invention.

I claim:—

1. Photographic material for the production of dyestuff images comprising a photographic colloid containing silver halide and dyed by means of a dyestuff which is fast to said colloid, resistant to ordinary photographic treating baths and which absorbs substantially all of the visible rays of the spectrum but transmits invisible rays, and a sensitizer sensitizing said colloid in respect to said invisible rays.

2. Photographic material for the production of dyestuff images comprising a photographic colloid containing silver halide and dyed by means of a dyestuff which is fast to said colloid resistant to ordinary photographic treating baths and which absorbs substantially all of the visible rays of the spectrum but transmits infra-red rays and a sensitizer sensitizing said colloid for infra-red rays.

3. Photographic material for the production of

dyestuff images comprising a silver halide emulsion dyed by means of Naphthylamine Black 4E and a sensitizer sensitizing said emulsion in respect to infra-red rays.

5 4. Photographic material for the production of dyestuff images comprising a silver halide emulsion dyed with Diamine Black BO and a sensitizer sensitizing said emulsion in respect to infra-red rays.

10 5. Photographic material for the production of dyestuff images comprising a silver halide emulsion dyed by means of Sudan Black B and a sensitizer sensitizing said emulsion in respect to infra-red rays.

15 6. Photographic material for the production of dyestuff images comprising a colloid containing silver halide and sensitized in respect to infra-red rays by means of Cryptocyanine 8, said colloid

being dyed with a dyestuff which is fast thereto and which absorbs substantially the whole of the visible rays of the spectrum, transmits infra-red, and is resistant to ordinary photographic treating baths.

7. Photographic material for the production of dyestuff images comprising a photographic colloid containing silver halide and dyed by means of a dyestuff which is fast to said colloid, resistant to ordinary photographic treating baths 10 and which absorbs substantially all of the visible rays of the spectrum, absorbing different of said visible light rays in different degree but transmitting invisible rays and a sensitizer sensitizing said colloid in respect to said invisible rays and 15 those light rays for which the absorption of the dyestuff has a minimal value.

BÉLA GASPAR.
